FIG. 2

INVENTOR.

EDWIN PALMER SCRIGGINS

BY

Edwin Palmer Scruggins

ATTORNEY

UNITED STATES PATENT OFFICE

135,440

DESIGN FOR A PANTY-GIRDLE

Edwin Palmer Scriggins, East Orange, N. J., assignor to Jantzen Knitting Mills, Portland, Oreg., a corporation of Oregon

Application February 2, 1943, Serial No. 109,412

Term of patent 7 years

To all whom it may concern:

Be it known that I, Edwin Palmer Scriggins, a citizen of the United States, residing at East Orange, county of Essex, and State of New Jersey, have invented a new, original, and ornamental Design for a Panty-Girdle, of which the following is a specification, reference being had to the accompanying drawing, forming a part thereof.

Fig. 1 is a front view of a panty-girdle, showing my new design;

Fig. 2 is a rear view thereof.

I claim:

The ornamental design for a panty-girdle, as shown.

EDWIN PALMER SCRIGGINS.
